UNITED STATES PATENT OFFICE.

THOMAS G. HODGINS, OF LUCAN, AND ELI HODGINS, OF BIDDULPH,
CANADA.

MANURE-CARRIER.

SPECIFICATION forming part of Letters Patent No. 637,116, dated November 14, 1899.

Application filed January 3, 1898. Serial No. 665,371. (No model.)

To all whom it may concern:

Be it known that we, THOMAS G. HODGINS, of the village of Lucan, and ELI HODGINS, of the township of Biddulph, in the county of 5 Middlesex, in the Province of Ontario, Canada, have invented a new and useful Manure-Carrier, of which the following is a specification.

This invention relates to a track for supporting a carriage which is particularly adapted for conveying manure from one place to another, but it may be used with equal advantage for conveying other material; and this invention consists in the novel construction and combination of parts hereinafter fully described and claimed, the object being the provision of a simple, strong, and durable device for this purpose, one which will be inexpensive to manufacture, light and easy to 20 operate, and efficient in practical use.

Reference is had to the accompanying drawings, wherein—

Figure 1 is a side elevation of a manure-carrying apparatus embodying our invention. 25 Fig. 2 is a plan view of same. Fig. 3 is a detail plan view of another curved guide by means of which one portion of the track extends at an angle to the other portion and at a different angle to that shown in Fig. 2. Fig. 30 4 is a detail side elevation of the track-wire hanger. Figs. 5, 6, and 7 are enlarged detail end, plan, and side views, respectively, of the curved guide which permits one portion of the track to extend at an angle to the other 35 portion and at the same time permits the carriage to pass over safely. Figs. 8 and 9 are enlarged detail side and end views, respectively, of the carriage. In Fig. 9 part of the guide L', lever J³, and side bar K are cut 40 away and the ring L³ is not shown, in order to more clearly illustrate one of the swivel-frames.

A designates the track-wire, the ends of which are firmly secured to the posts B and 45 B' by loops a', formed on the ends of said wire, engaging with hooks b², screwed into or otherwise secured to said posts; but the ends of said track-wire may be secured to any suitable support in any manner or by any means 50 found most suitable or convenient.

C designates a turnbuckle with which the

track-wire A is provided for the purpose of tightening said track-wire when setting up or to take up any subsequent sagging thereof.

The screw-hook b², which secures the end 55 of the track-wire A to the post B', extends through said post, as shown in Fig. 1, and is provided with a nut b³. When so constructed, by turning the nut b³ on the outer end of the screw-hook b² the track-wire may be further 60 tightened when setting up or to take up any subsequent sagging.

D D designate hangers which are secured to the joists E, and said hangers are provided with an upturned end d' for the purpose 65 which will be hereinafter set forth, and in said upturned end d' the groove or recess d² is formed, in which the track-wire A is securely held and supported against accidental displacement.

E designates a stop-block which is adjustably secured to the track-wire A by a set-screw e' or other suitable securing device.

F designates a curved guide in which the recess F' is formed and which is provided 75 with the arms F², and G designates a bail the open ends of which are connected to the arms F² and the arched portion with the hook H, secured to the post I or other suitable support.

J designates a box or receptacle, and J' a flap-bottom hinged at one side thereto by the hinges J², and J³ designates a lever pivotally mounted on the pivot-bolt J⁴, supported in the lugs J⁵, and the latter are secured to the box 85 J. J⁶ designates a shoulder formed on this lever J³, on which the flap edge of the bottom J' is supported when holding it closed.

J⁷ designates a flange secured to or formed with the lever J³, and in this flange J⁷ an 90 opening J⁸ is formed, and J⁹ is a bolt fixed to the box J and so arranged as to project through the opening J⁸ of the lug J⁷, and J¹⁰ is a coil-spring encircling the bolt J⁹ and compressed between the box J and flange J⁷, and 95 said spring being so compressed adjusts the upper end of the lever from and the lower end toward the box J and with the shoulder J⁶ under the bottom J'.

K K designate side bars which connect the 100 box or receptacle J with the beam L at two opposite sides.

5 L' designates a guide in which a slot L² is formed, and said guide is secured to the beam L, and through the slot L² in this guide the upper end of the lever J³ projects in order that it may be held in line as it is adjusted to or from the beam L, and L³ is a ring secured to said guide, or it may be secured to any other portion of the box J, and L⁴ is a pulley the block of which is secured by the 10 hook L⁵ to the post B', and L⁶ is a rope which is secured at one end to the ring L³ and extends over the pulley L⁴ and back again to the box J or to any point within the barn. The object of this construction is to render it 15 unnecessary to go out of the barn to carry or unload the manure.

10 The side bars K K and the lever J³ are each formed in two sections k' and k² and j' and j², respectively, which sections are secured together by the bolts k³ and j³, respectively, and said sections may be provided with a series of bolt-holes, so that one section may be adjusted longitudinally on the other section to shorten or lengthen the side bars K and lever 20 J³, as desired, and the bolts inserted in holes in the sections to hold them at this point.

25 M M designate grooved wheels which are supported by and revolve perfectly free on the axles N, and the latter are supported in the swivel-frames O, and each of said swivel-frames O is secured to the beam L by a bolt O', around the shank of which bolt the frame O turns horizontally for the purpose which will be hereinafter set forth.

30 35 This apparatus is set up as follows: The track-wire A is placed in position by firmly securing one end thereof to the post B, which may be a post or pillar forming part of the structure of the barn, and the other end to a post B', outside of the barn and beyond the place where the material is to be deposited. Then as the point where the track-wire extends around a corner, or where the traveling 40 of the carriage thereon would be interfered with by any object, or where from any reason it would be an advantage to have one portion of the track extend at an angle to the other portion, the curved guide F is adjusted in contact with said track-wire and the latter 45 drawn clear of the corner or other object and held in said position by the bail G, hook H, and post I, as shown in Fig. 2. After which, by means of the turnbuckle C or nut b³, or both, the track is drawn taut or a tension formed 50 55 thereon to firmly support the carriage. The hangers D are then secured to the joists E at suitable intervals and in such a position that the recess d² will be in line with the track-wire A, and the latter is adjusted and supported in said recess in order to prevent excessive sagging of the track-wire when a heavily-loaded carriage is traveling thereon. The swivel-frames O have an opening O² formed in one side thereof, as shown particularly in Fig. 9, by means of which they may be adjusted over the track-wire A until the grooved wheels M rest thereon, as shown in

60 Figs. 8 and 9. These swivel-frames O are formed with a downwardly-projecting portion O³, which extends below the track-wire A 70 and also below the curved guide F for the purpose of avoiding and completely preventing any possibility of the carriage jumping off or being accidentally disengaged from said track-wire or curved guide. At the same time 75 the openings O² in the swivel-frames O provide a convenient means for placing the carriage on or removing it from the track-wire, and the hangers D are provided with the upturned end d' and with the depressed portion d³, as 80 shown in Fig. 4, and the arms F² are set down below the curved guide F, as shown in Fig. 5, to prevent the downwardly-projecting portion O³ of the swivel-frame O from interfering with these parts when the carriage is 85 traveling on the track-wire A.

90 When this apparatus is in use in a stable, the track-wire A extends past the stalls within a convenient distance thereof and out through the doorway, and when the carriage is not in 95 the vicinity of the doorway the tension of the wire is sufficient to hold it against the top of the doorway, so that by cutting a notch in the top of the door to receive the track-wire the latter may extend through the doorway 95 and at the same time not interfere in any way with the tight closing or locking of the stable-door. Again, the weight of the carriage on the track-wire, when in the vicinity of the doorway, causes said wire to sag, so 100 that when the loaded or unloaded carriage is passing through the doorway the track-wire will sag sufficient to permit the carriage to pass freely through said doorway.

105 The box J when loaded is adjusted on the track-wire A toward the post B' by the rope L⁶ until the upper end of the lever J³ comes in contact with the stop-block E, which adjusts the upper end of said lever toward and the lower end from the box J and the shoulder J⁶ from beneath the flap edge of the bottom J', when the bottom by its own weight, supplemented by the weight of the load, will automatically and instantly dump the contents of the box J, after which by another 115 rope attached to the ring L³ the carriage may be returned to the stable, so that if the curved guide F was located just within the stable-door the operator would not be required to move out of the stable in order to carry or 120 dump the load at the required place.

125 The side bars K K and lever J³ are each formed in two sections, as before described, which sections are adjustable on one another to permit the box J to be adjusted a convenient height from the stable-floor in order that it may be readily and easily loaded or to adapt it to clear any outside obstacle.

130 When the track has been set up, the operation of transporting and dumping the load is very simple. After the box J has been returned to the stable for another load the bottom J' is adjusted to the position shown in Fig. 8 and the shoulder J⁶ of the lever J³ en-

gaged therewith, also as shown in the same figure. While the bottom is thus securely held, the box J may be loaded, after which the carriage is adjusted in the direction in which the track-wire extends, and while passing over the curved guide F the swivel-frames O permit the pulleys to adapt themselves to said curved guide, and thus avoid and completely prevent the grooved wheels M from binding on or disengaging from the curved guide while passing over the latter, and the stop-block E is secured to the track-wire at the place where it is required to dump the load, so that as soon as the carriage arrives at this point the upper end of the lever engages with the stop-block E, as before described, and releases the flap end of the bottom J', which automatically dumps the load, after which the carriage is returned by any suitable means, one of which is hereinbefore described, and the track-wire resting free in the recess F' of the curved guide F and the latter being secured to the post I by the arch of the bail G engaging with the hook H the curved guide F freely rises and falls with the tension and sagging, respectively, of the track-wire and adapts itself to the track-wire when in either position, and the carriage always retains its upright position irrespective of whether it is passing over the curved guide loaded or unloaded.

The result is that a simple, strong, and durable apparatus is provided, one which is inexpensive to manufacture and efficient in practical use, and one by which one portion of the track may extend at an angle to the other portion, or by the use of a number of curved guides said track may extend in a circle and permit the carriage to pass around the same.

This apparatus has been described in connection with transporting manure from a stable and automatically dumping the same at

any required point; but it may be used with equal advantage for transporting manure to the field for distribution or for transporting and dumping any material, and we have found by experiment that the construction herein shown and described gives the best results. At the same time, while we prefer the same, we do not wish to limit ourselves to the details thereof, as they may be modified in various ways without departing from the spirit of our invention.

Having thus described our invention, we claim—

1. A track, A, in combination with a curved guide, F, in which a recess, F', is formed and which is provided with the arms, F², the bail, G, hook, H, and post or support, I, substantially as and for the purpose set forth. 60

2. A track, A, curved guide, F, and stop-block, E, in combination with a carriage consisting of the wheels, M, M, the swivel-frames, O, O, open at one side, and formed with the downwardly-projecting portion, O³, beam, L, side bars, K, K, box, J, provided with a hinged bottom, J', and lever, J³, provided with a shoulder, J⁶, substantially as and for the purpose set forth. 70

3. A track, A, curved guide, F, hangers, D, turnbuckle, C, and stop-block, E, in combination with a carriage consisting of, a box, J, a hinged bottom, J', lever, J³, provided with a shoulder, J⁶, the side bars, K, K, beam, 75 L, swivel-frames, O, open at one side and provided with the downwardly-projecting portion, O³, and the wheels, M, mounted in said swivel-frames and traveling on the track-wire, substantially as and for the purpose set forth. 80
